W. H. GRIFFITH.

LIFTING JACK.

APPLICATION FILED NOV. 23, 1917. RENEWED JULY 14, 1919.

1,315,929.

Patented Sept. 9, 1919.

William H. Griffith, ^{Inventor}
By Verusub, ^{Attorney}

UNITED STATES PATENT OFFICE.

WILLIAM H. GRIFFITH, OF WORTHINGTON, INDIANA.

LIFTING-JACK.

1,315,929.

Specification of Letters Patent.

Patented Sept. 9, 1919.

Application filed November 23, 1917, Serial No. 203,589. Renewed July 14, 1919, Serial No. 310,811.

To all whom it may concern:

Be it known that I, WILLIAM H. GRIFFITH, a citizen of the United States of America, residing at Worthington, in the county of 5 Greene and State of Indiana, have invented certain new and useful Improvements in Lifting-Jacks, of which the following is a specification.

My invention relates to an improvement 10 in lifting jacks and the object is to dispense with bolts in large measure and otherwise reduce the number of parts in the working mechanism of the jack.

In the accompanying drawings Figure 1, 15 is a view in longitudinal section.

Fig. 2 is a vertical transverse section; Fig. 3 is a view of the holder 5.

A, represents the main standard of my improved lifting jack. B is the base to 20 which the standard is secured by bolt or other means 1.

C and D, are the upper and lower runners mounted and adapted to slide on the standard A, in the usual manner. An L-shaped 25 lever A⁷ is provided with the U shaped bearings 2, one on either side whereby it is detachably pivoted between the two rounded studs 3, projected inwardly from opposite directions and the hand lever A¹, is pivotally secured to the upper runner C, and also 30 to the upper end of the L shaped lever A⁷. A spiral spring 4, housed within the lower runner D, is interposed between one end of the L shaped lever A⁷ and the wall of the 35 runner for maintaining the normal locking position of the runner D, upon the bar or standard A, in the usual manner.

As a means for clutching the upper runner C, to the bar or standard, the holder A⁵ is 40 provided. This has a hole 6, through it to receive and loosely fit the main standard A, upon which it may be said to float loosely and the end 7, of this holder A⁵, extends loosely into the recess 9, formed between 45 the bolt hole in the upper runner C, and the wall thereof, as a pivotal point from which it is capable of a limited vibration and a spiral spring 8, inserted between this holder and the wall of the upper runner C, 50 forces the holder A⁵ normally up to cause it to clutch upon the standard A.

In order to lift the load the runners are raised to a suitable height on the standard

A, then the handle A¹ is successively lowered and raised thus alternately lifting one runner C, and then the other runner D.

To lower the runners on the bar or standard, the handle A¹, is swung into suitable position to loosen the grip of the lower runner upon the standard A, and the operator 60 presses the protruding end of the holder A⁵, down whereupon both runners C and D may be slid to the required position on the bar or standard A.

To lower the runners, by step by step motion the handle A¹ is pressed down by one hand and the end 7 of holder A⁵ by the other where it is held while the handle is again raised until the runner C, has descended. The holder A⁵, is then released whereby it 70 grips upon the bar or standard and holds the load at that point until the lower runner D, has been lowered in precisely the same manner except that the handle is lowered as the lower runner D, is pushed down. This 75 method is continued until the load is lowered to any desired point.

To drop the load raise the trip until holder A⁵ is in released position, then raise the handle A¹, until the runner C, descends 80 striking the runner D, which will release both holders and drop the parts to the bottom of the bar or standard A.

I claim:

1. A lifting-jack containing a standard, 85 two runners loosely mounted thereon, a handle pivoted to one runner, a lever pivoted to the handle and to the other runner, and a holder housed within one runner at a point between said pivots and the main or operative part of the runner, said runners and holder slidably mounted on the standard and held assembled by the standard.

2. A lifting-jack containing a standard, 95 two runners loosely mounted thereon, a handle pivoted to one runner, a lever pivoted to the handle and to the other runner, a holder housed within one runner at a point between said pivots and the main or operative part of the runner, said runners and holder slidably mounted on the standard and held assembled by the standard, a spring interposed between the holder and the runner in which it is housed, and another spring interposed between one end of the lever and the runner 100 to which it is pivoted.

3. A lifting-jack having a standard, two hollow runners and a holder mounted to slide on the standard, the holder housed within one of the runners, a handle pivoted to one runner, an L-shaped lever pivoted to the handle and provided with a U-shaped bearing which detachably receives a stud in one of the runners, said standard holding the parts together and while in place pre-

venting the lever from being detached from 10 the stud and its runner.

In testimony whereof I affix my signature in the presence of two witnesses.

WILLIAM H. GRIFFITH.

Witnesses:

GEO. M. NOTTER,
L. R. BOOZE.
